DESIGN FOR A HANDLE FOR KITCHEN UTENSILS OR THE LIKE

John W. Abell, Torrington, Conn., assignor to Turner & Seymour Manufacturing Company, Torrington, Conn., a corporation of Connecticut

Application December 5, 1938, Serial No. 81,593

Term of patent 14 years

To all whom it may concern:

Be it known that I, John W. Abell, a citizen of the United States, residing at Torrington, county of Litchfield, and State of Connecticut,
have invented a new original, and ornamental Design for a Handle for Kitchen Utensils or the like, of which the following is a specification, reference being had to the accompanying drawing, forming part thereof.

In the drawing:

Fig. 1 is a front view of a handle, showing my
new design;

Fig. 2 is a side view thereof; and

Fig. 3 is a view of the forward end of the handle.

I claim:

The ornamental design for a handle for kitchen utensils or the like, substantially as shown.

JOHN W. ABELL.
